Primary Examiner — Raphael Barkai(74) *Attorney, Agent, or Firm* — Nixon & Vanderhye, P.C.(57) **CLAIM**

The ornamental design for a “television set,” as shown and described.

DESCRIPTION

FIG. 1 is a perspective view of a television set in accordance with our new design;

FIG. 2 is a front elevation view thereof;

FIG. 3 is rear elevation view thereof;

FIG. 4 is a top plan view thereof;

FIG. 5 is a bottom plan view thereof;

FIG. 6 is a left-side elevation view thereof; and,

FIG. 7 is a right-side elevation view thereof.

Subject matter shown in dashed lines is for environmental purposes only and forms no part of the claimed invention.
